(57) **CLAIM**

The ornamental design for an electrical receptacle, as shown and described.

DESCRIPTION

FIG. 1 is an upper perspective view of an electrical receptacle showing our new design;

FIG. 2 is a lower perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings are included for the purpose of illustrating portions of the electrical receptacle that form no part of the claimed design.
